UNITED STATES PATENT OFFICE.

WILLIAM E. GOOD, OF PHILADELPHIA, PENNSYLVANIA, ASSIGNOR TO THE SOUTHWARK FOUNDRY AND MACHINE COMPANY, OF SAME PLACE.

BLOWING-ENGINE OR COMPRESSOR.

SPECIFICATION forming part of Letters Patent No. 515,331, dated February 27, 1894.

Application filed August 8, 1892. Serial No. 442,489. (No model.)

To all whom it may concern:

Be it known that I, WILLIAM E. GOOD, of the city and county of Philadelphia, State of Pennsylvania, have invented a certain new 5 and useful Improvement in Blowing Engines or Compressors, of which the following is a true and exact description, reference being had to the accompanying drawings, forming a part of this specification.

10 My invention relates to blowing engines or compressors, and has for its object to simplify and improve the construction and mode of operation of such engines; particularly, with reference to the valves through which the air 15 is discharged from the main cylinder, or tub, as it is generally called.

The nature of my improvement will be best understood as described in connection with the drawings in which it is illustrated and in 20 which—

Figure 1 is an elevation of a blowing engine provided with my improvements; Fig. 2 a vertical section through the discharge valve taken on the line xx of Fig. 4; Fig. 2^a a cross-25 section through the valve and its bearings taken on the line zz of Fig. 4; Fig. 3 a section through the admission valve taken on the line yy of Fig. 4; Fig. 4 a horizontal section taken on the line vv of Fig. 2. Fig. 5 is 30 a diagram illustrating the movements of the crank of the engine; Figs. 6, 7, 8, and 9 views illustrating the various positions of the discharge valve and its connected mechanism corresponding with the various points of the 35 movement of the crank. Fig. 10 is a diagram again illustrating various positions of the crank; Figs. 11, 12, 13 and 14 views illustrating the different positions of the admission valve corresponding with different positions 40 of the crank, and Fig. 15 is a view illustrating a simple modification of my invention.

A indicates the foundation of the engine, B the frame thereof, on which is suitably supported the main shaft C, having crank C', 45 and the fly-wheel or wheels D. Supported on the frame are the steam cylinder G and the main cylinder or tub of the compressor H.

E indicates one of the connecting rods extending from the crank to pins F² secured to a suitably guided cross-head, which in turn 50 is secured to the piston rod F which extends

between the tub and the steam cylinder, being attached to the piston F' in the tub, and to a similar piston in the steam cylinder.

All the above parts being familiar in construction I have not thought it necessary to show them in detail, except that in Fig. 2 I show a portion of the cross-head indicated by the letter F³ as having a special construction which I will hereinafter describe. 55

On each head of the tub is a casing H' which forms a receiver for the compressed air, H² H² indicating the chambers through which the air is admitted to the tub H. 60

I indicates the admission valve which is of 65 the gridiron type working over a series of slot-like openings in each end of the tub. J indicates the discharge valve which is also a gridiron valve of the same general character as the valve I, and I will here note that these 70 valves, and especially the delivery valves, should be constructed in accordance with my Patent No. 381,876 of April 24, 1888, that is to say, the valves should be given a certain amount of play between their seats on the 75 head of the tub, and their back bearings indicated by the letter j, so that as described in my said patent they will be lifted from their seats when the pressure within the tub exceeds that within the receiver. 80

Referring now to the admission valve, I' indicates the valve spindle by which it is actuated; this spindle is attached at its end to a cross-head Q supported on guide Q', and provided with an oblique curved slot Q², 85 into which slot extends a pin preferably provided with a roller R' attached to the end of a lever R which in turn is secured to a rock shaft r. From this rock-shaft extends a lever arm R² which by means of a rod R⁴ is connected with the arm R⁵ of a pivoted bell-crank-lever R⁵ R⁶, the arm R⁶ of which is connected by means of a rod R⁷ with a lever R⁸ which lever is pivotally attached at one end to a portion of the connecting rod E, as shown 90 by a projecting toe E' of the said connecting rod; and the other end of rod R⁸ is suitably supported as shown, for instance, in a pivoted guide-block R⁹ in which it is free to slide. The novel features of this construction consist essentially in dispensing with connections 95 to an eccentric on the shaft and communicat- 100

ing motion to the admission valve from the end of a connecting rod E. It will be readily seen that the desired motion is obtained by the mechanism I have described, and obviously the simplicity of this arrangement is advantageous not only in diminishing the cost but in eliminating a number of connections with the crank shaft, which are more or less in the way. This feature, however, is claimed in another application filed by me August 15, 1892, Serial No. 443,146, and in this case will only be claimed in combination with the devices for actuating the discharge valve. Slot Q² in the cross-head Q is formed of a curved portion q corresponding in curvature with the arc described by the pin in the end of lever R, and a portion q' of different curvature, or, as shown, having a straight up and down direction.

Referring now to Figs. 10 to 14, Fig. 11 represents the position of the valve and its actuating devices when the crank C' is in the position represented by a in the diagram Fig. 10. As the crank moves downward the lever arm R also moves downward, and acting on the straight part of groove Q² pulls the cross-head Q outward opening the admission valve attached to it as indicated in Fig. 12, which represents the position of the valve when the crank is at the point marked b in the diagram. As the crank continues to move downward the lever arm R moves gradually upward closing the valve, which, however, is not entirely closed until the crank reaches the position marked c in the diagram, with which Fig. 13 corresponds. The further or upward and downward movement of the lever arm R corresponding with the movement of the crank from c through d to a effects no change in the position of the valve as it is moving in the circular arc of the slot Q²; Fig. 14, representing the position of the valve and its parts corresponding to the crank position indicated at d.

Referring now to the discharge valve and the mechanism for actuating it, these valves are attached to valve rods J' which extend through suitable stuffing boxes indicated at J², and are attached to pistons K, which pistons are situated in cylinders L, the pistons being preferably formed or connected with plunger extensions K³ which extend through a somewhat contracted end L' of the cylinder L. M is a passage or conduit which leads from the tub to cylinder L. In Figs. 2 and 4 it is provided with an opening M' leading into the head of the tub, an opening M², communicating with a passage L² leading into the end of cylinder L, and an exhaust opening M³, and a lining N is secured in this conduit or casing, said lining being open at both ends and provided with proper orifices N' communicating with the passage M. In the lining N works a valve O operated by means of a rod O' and lever arm O² connected to a rock-shaft P², which shaft is operated by means of a lever or levers as indicated at O⁴ or O⁷,

said levers being directly or indirectly connected by rod O⁵ with a pivoted lever O⁶, one end of which is secured in a pivoted guide block F⁴ secured to the cross-head F³. The lever arm preferably extends through an opening F⁵ in said cross-head as indicated in Fig. 2. As indicated in Figs. 1 and 2 the lever O⁴ which actuates the rock-shaft P² at the bottom of the tub is connected with levers O⁷ which actuate the rock-shaft at the top of the tub by a rod O³, and, of course, the levers O⁴ and O² on the one shaft and the levers O⁷ and O² on the other shaft are so arranged that their motion is inverted as to each other, because, the motion of the valves O and of other parts to which I shall hereinafter refer, occur alternately at the top and bottom of the tub. At the back end of the cylinder L is an escape passage L³ which may or may not be provided with a regulating cock as shown, and in front of it are other escape passages L⁴. P P are wipers secured to the rock-shaft P², and arranged to come against the end of the plunger extension K³ of the piston K.

Referring now to the diagrams Figs. 5 to 9, Fig. 6 represents the position of the valve O when the crank C' is at the position marked A in the diagram Fig. 5. It will be seen that in this position the wipers are turned back away from the end of the plunger extension K³. Fig. 7 represents the position of the valve when the crank is at the point marked B in the diagram, and it will be seen considering Figs. 2 and 4 in connection with Fig. 7 that while the crank is moving from A to B there is a connection through the port M', casing N, the port M² and the port L² between the interior of the tub and the adjoining or front end of cylinder L, and during these movements of the crank, and while the piston is moving from the point indicated in Fig. 6 to the point indicated in Fig. 7, the pressure of air in the tub is sufficient, acting upon the broad face K' of the piston K to force it backward or away from the tub and open the discharge valve J. As this motion of the piston and valve is very violent and sudden, and as the parts have very considerable weight, I find it advisable to avoid undue shock to provide restricted orifices L⁴ somewhat in advance of the back end of the cylinder L, so that the air contained in the annular chamber l at the back of the piston will serve as a cushion to take up and overcome the momentum of the parts, and yet, be free to escape after having served its purpose, so that it will not tend to close the discharge valve, and in addition I have the air cushion in the extreme rear of the cylinder with its escape passage L³ serving the same purpose. As the crank moves from the point B to the point marked C the connection between the tub and cylinder is cut off by the valve O, which as it moves forward toward the tub opens the connection between the port M and the atmosphere, so that the compressed air in

cylinder L is free to escape, but at the same time, it will be noted that the wipers P have not yet come in contact with the back of the plunger extensions K³; this contact, however, 5 occurs at or about the position of the crank indicated at C (see Figs. 5 and 8), and as the crank moves from C to D the wipers move gradually forward until at the point D they have pushed the piston K back to the front 10 end of the cylinder and entirely closed the discharge valve, or at least, closed it as far as its gridiron feature is concerned, the play of the valve upon its seat permitting a slight opening even after it is so closed.

15 The success and efficiency of the construction which I have above described depend largely upon a number of rather obscure conditions. It might be supposed that the discharge valve operated by the mechanism I 20 have described would be opened so early in the movement of the tub piston toward it that the air in the receiver would flow back into the tub; this, however, is not the case; because, in the first place, the compressed air in 25 moving the valve has to overcome the frictional resistance offered by the adhesion of the discharge valve to its seat under the pressure of the air in the receiver; this latter factor, of course, diminishes as the pressure 30 in the tub increases, but by properly proportioning the area of the piston K it is sufficient to prevent the opening of the valve too soon; and I have ascertained that though the discharge valve be open while the pressure of 35 the receiver is still greater than that in the tub, there will be no appreciable flow of air back into the tub, because, before the air can get in motion, the rapidly moving tub piston will have compressed the air in the tub to a 40 point equal to or in excess of the pressure in the receiver. I may say that, to a certain extent, my invention is based upon my discovery of the above facts.

Obviously the device is operative when no 45 exhaust passage leads from the conduit M, the wipers then pushing the valve shut against the resistance of the air in cylinder L and forcing it back into the tub. In this case the opening of conduit M into the tub is conveniently situated as shown in Fig. 15, so 50 that when the piston F' is at the end of the stroke the conduit will exhaust into the tub behind it. In this construction no valve O is necessary, but such a valve is convenient 55 as a means of regulating the time of admission to cylinder L with respect to the position of the tub piston F' in its stroke.

In speaking of the closing of the discharge valve I refer to it as taking place at the end 60 of the stroke of the compressing piston, but do not mean to limit myself to a simultaneous operation. In fact, while the valve begins to close some time before the piston F' reaches the end of its stroke I find it convenient not to entirely close it until said piston 65 has moved back about half an inch, in an engine having a five foot stroke.

Having now described my invention, what I claim as new, and desire to secure by Letters Patent, is—

1. In a blowing engine or compressor the combination with the tub, of a discharge valve, a receiver, a cylinder connected with the tub but not with the receiver, a piston working in said cylinder and connected with the discharge valve, said tub and cylinder, the port connecting them and the piston working in the cylinder being combined as described, and so that the pressure in the tub will act directly against the valve piston in a 75 direction to open the valve and positively actuated mechanism driven by moving parts of the engine arranged to close the discharge valve at the end of the stroke of the compressing piston. 80

2. In a blowing engine or compressor the combination with the tub, of a discharge valve, a cylinder L, a piston working in said cylinder and connected with the discharge valve, a conduit M connected with the tub 90 and the cylinder L as described, a valve O working in said conduit so as to alternately connect and disconnect cylinder L with the tub, means for actuating said valve connected with moving parts of the engine so as to connect the tub and cylinder during the motion of the compressor piston toward the discharge valve, and means adapted to close the discharge valve also connected with the moving parts of the engine and so as to close the 95 valve at the end of the compressing stroke of the piston. 100

3. In a blowing engine or compressor the combination with the tub, of a discharge valve, a cylinder L, a piston working in said 105 cylinder and connected with the discharge valve, a conduit M connecting with the tub, the cylinder L and the exhaust as described, a valve O working in said conduit so as to alternately connect cylinder L with the tub 110 and the exhaust, means for actuating said valve connected with moving parts of the engine so as to connect the tub and cylinder L during the motion of the compressor piston toward the discharge valve, and means adapted 115 to close the discharge valve, also connected with moving parts of the engine and so as to close the valve at the end of the compressing stroke of the piston.

4. In a blowing engine or compressor the combination with the tub, of a discharge valve a cylinder L having a plunger piston working in it and connected to the discharge valve, a conduit M connecting with the tub, the end of cylinder L, and the exhaust as described, a valve O working in said chamber so as to alternately connect cylinder L with the tub and the exhaust, means for actuating said valve connected with the moving parts of the engine so as to connect the tub and 125 cylinder L during the motion of the compressor piston toward the discharge valve, means adapted to close the discharge valve 130 also connected with moving parts of the en-

gine, and so as to close the valve at the end of the compressing stroke of the piston, and a restricted air escape passage or passages leading from the rear end of cylinder L.

- 5 5. In a blowing engine or compressor the combination with the tub, of a discharge valve, a cylinder having one end connected with the tub near its end, a valve arranged in the connecting passage and operating to
  - 10 alternately connect the cylinder with the tub and the exhaust, a piston working in said cylinder and connected with the discharge valve, positively actuated mechanism arranged to close the discharge valve and force
  - 15 the piston back in its cylinder, and an air chamber connected with the cylinder and provided with a restricted orifice for the escape of air, said chamber being arranged as described to check the backward motion of the
  - 20 valve and piston attached thereto.
  6. In a blowing engine or compressor the combination with the tub, of a discharge valve, a cylinder L, a piston K working in said cylinder and connected with the discharge
  - 25 valve, a conduit M connecting with the tub, the cylinder L and the exhaust, a valve O working in said casing, a rock shaft P² having secured to it a lever O², connected with valve O and one or more wipers P arranged to act
  - 30 on piston K as described, and mechanism connecting said rock shaft with a moving part of the engine to actuate it as described.
  7. In a blowing engine or compressor the combination with the tub, of a discharge

7. In a blowing engine or compressor the combination with the tube of a discharge

valve, a cylinder L, a piston K working in said cylinder and connected with the discharge valve, a conduit M connected with the tub, the cylinder L and the exhaust, a valve O working in said conduit, a rock shaft P² having secured to it a lever O² connected with valve O, and one or more wipers P arranged to act on piston K as described, and a piston rod connected with the main compressing piston, a pivoted lever O⁶ actuated by said rod, and a connecting rod O⁵ connecting said lever to a lever on the rock shaft all substantially as specified. 35 40 45

8. In a blowing engine or compressor having discharge and admission valves and a crank shaft, a cylinder connected to the tub by a conduit, a piston working in said cylinder and operating upon the discharge valve as described so as to open it as the pressure in the tub increases, positively actuated mechanism arranged to close the discharge valve at proper times, a connecting rod E extending from the crank of the engine, a lever R^3 pivotally secured to said rod or extension thereof at one end, and having its other end supported so as to permit longitudinal motion, a cross-head Q attached to the admission valve, a rock shaft r having a lever arm R connected with the cross-head as described, and means substantially as specified for communicating motion from lever R^3 to rock shaft r . 50 55 60
